Patented Apr. 10, 1923.

UNITED STATES PATENT OFFICE.

JESSE J. HEAP, OF NEW YORK, N. Y., ASSIGNOR TO UNION SPECIAL MACHINE COMPANY, OF CHICAGO, ILLINOIS, A CORPORATION OF ILLINOIS.

PLAIT FOLDER FOR SEWING MACHINES.

Application filed November 11, 1919, Serial No. 337,121. Renewed March 2, 1923.

To all whom it may concern:

Be it known that I, JESSE J. HEAP, a citizen of the United States, residing at New York, in the county of New York, State of New York, have invented certain new and useful Improvements in Plait Folders for Sewing Machines, of which the following is a description, reference being had to the accompanying drawing and to the figures of reference marked thereon.

The invention relates to new and useful improvements in folders for sewing machines, and more particularly to a folder for folding a facing strip to form a plait for attachment to shirts or the like.

An object of the invention is to provide a folder for directing and folding the edges of a facing strip, and for simultaneously forming from the body portion of the facing strip a plait which is centrally superposed upon said facing strip.

In the drawings which show by way of illustration one embodiment of the invention;

Figure 1 is a view showing more or less diagrammatically certain parts of a sewing machine having my improved folder applied thereto,

Fig. 2 is a view showing more or less diagrammatically the strip as it is being folded, and also the body fabric to which the strip is attached and the position of the needles for forming the lines of stitching,

Fig. 3 is an enlarged longitudinal sectional view through the folder and a portion of the work support of the sewing machine,

Fig. 4 is a plan view of the folder,

Fig. 5 is a sectional view on the line 5—5 of Fig. 3,

Fig. 6 is a sectional view on the line 6—6 of Fig. 3, and

Fig. 7 is a view showing more or less diagrammatically and in section, the body fabric, the plait attached thereto, and the position of the needles for forming the lines of stitching which secure the plait to the body fabric.

The invention is directed broadly to a folder which is provided with folding and guiding means for directing and turning in the edges of the facing strip and for simultaneously forming a superposed plait from the body portion of said facing strip. To this end, the folder is provided with spaced guiding walls shaped to receive the facing

strip and inturn the edges thereof. The upper wall is cut away from a point midway between its ends to the delivery end thereof so as to form spaced guiding edges, the distance between which gradually increases toward the delivery end of the folder. Secured to the lower member of the folder and extending through this recess is a rib which carries a plate which gradually increases in width toward the delivery end of the folder. The rib and plate co-operate with the guiding edges to fold the body portion of the facing strip and form a plait therefrom, the edges of the folded portions of which are disposed between and spaced from the edges of the folded portions of the facing strip.

Referring more in detail to the drawings, my improved folder is shown applied to a sewing machine having a presser foot 1, a work support 2, and the feed dog 3 for feeding the materials underneath the presser foot. As herein shown, the machine is provided with four needles, 5, 6, 7 and 8, and cooperating with each one is a looper, one of which is indicated at 9 in Fig. 1. Located in front of the presser foot is my improved folder which is indicated at 10. Said folder consists of a shank 11 having slots 12 formed therein through which screws may be inserted for clamping the folder to the work support 2 of the sewing machine. Attached to this shank is a lower guiding plate 13 and also an upper guiding plate 14. These guiding plates are so shaped as to gradually inturn the respective edges of a facing strip.

The facing strip is indicated at F in the drawings and the inturned edge portions of said facing strip are indicated respectively at f and f'. The garment to which the facing strip is secured is indicated at G, and the edge of the garment is preferably inturned as indicated at g. The body portion of the facing strip as formed by my improved folder is formed with a superposed plait which is indicated at P. This plait is formed by bending upwardly a portion of the facing strip centrally thereof and turning under sections thereof so as to form in substance a plait, the edge portions of which are inturned. In Fig. 7 of the drawings, these inturned sections are indicated at p and p'. The facing strip with its superposed plait is stitched to the garment by four lines of stitching. The needle 5 enters

the facing strip adjacent its outer edge and forms a line of stitching indicated at 15. The needle 6 passes through the superposed plait and the garment and forms a line of stitching indicated at 16. The needle 7 passes through the other edge of the plait and through the garment and forms a line of stitching 17, while the needle 8 passes through the facing strip adjacent its inner edge and also through the garment and forms a line of stitching 18.

The superposed plait is formed by cutting away the upper guiding plate so as to form spaced guiding edges 19 and 20 (see Figs. 4, 5 and 6). The recess between the guiding edges 19 and 20 gradually increases in width toward the delivery end of the folder. Mounted on the under guiding plate 13 and located in said recess is a rib 21. This rib projects upwardly to a point above the plane containing the guiding edges 19 and 20 and mounted on said rib is a plate 22. This plate 22 is tapered and increases in width toward the delivery end of the folder (see Fig. 4). The plate at the delivery end of the folder overlaps the edges 19 and 20 of the guiding member 14. The front end of the rib terminates at some distance in rear of the upper end of the recess between the edges 19 and 20, and the plate 22 extends forwardly beyond the rib and is curved downwardly as at 20^a between the guiding edges 19 and 20 and soldered or otherwise secured to the lower guiding member 13. The plate 22 therefore tapers substantially to a point at its front end, and in a sense, vanishes into the guiding member 13.

The plait P is formed by this rib and plate 22 and guiding edges 19 and 20. The body portion of the fabric will be at first raised by the plate 22 and then finally the inturned portions p and p' formed, so that as the facing strip passes from the folder it will have its edge portions turned under and the central portion of the strip formed into a plait. The edges of the folded portions of the plait will be well within and spaced from the edges of the folded portion of the facing strip after the edge portions are turned under. Said folder is provided with a bridge piece 23 which extends over the recess between the edges 19 and 20 at the front end thereof and is also provided with a bridge piece 24 which extends over the plate 22 at the delivery end of the folder. These bridge pieces hold the spaced upper sections of the folder against movement.

From the above it will be apparent that I have provided a folder wherein a flat strip of fabric is directed and guided so as to fold underneath the edge portions thereof and also to simultaneously form from the body portion of said strip, a superposed plait,

the edges of the folded portions of said plait being well within the marginal edges of the facing strip. In the finished article, the facing strip has the appearance of a double plait wherein the outer or superposed plait is smaller than the under plait and four lines of stitching pass through the double plait, which lines of stitching are approximately the same distance from the adjacent folded edge portions which are 75 stitched down by the respective lines of stitching.

It is obvious that minor changes in details of construction and arrangement of parts may be made without departing from the 80 spirit of the invention as set forth in the appended claims.

Having thus described the invention, what is claimed as new and desired to be secured by Letters Patent is:—

1. A folder for sewing machines including upper and lower guiding members shaped so as to receive, direct and turn underneath the edge portions of a facing strip, the upper member being formed with a recess centrally thereof which increases in width toward the delivery end of the folder, a rib carried by the lower guiding member and located in said recess, a plate carried thereby, said plate and rib being shaped so as to form a plait from the body portion of the facing strip passing through the folder.

2. A folder for sewing machines including upper and lower guiding members shaped so as to receive, direct and turn underneath the edge portions of a facing strip, the upper member being formed with a recess centrally thereof which increases in width toward the delivery end of the folder, a rib carried by the lower guiding member and located in said recess, a plate mounted on said rib, said plate having its receiving end vanishing into the lower guiding member and increasing in height toward the delivery end to a point well above the upper guiding member, and overlapping the edges of the upper guiding member alongside of said central recess, said plate increasing in width from its front end to the delivery end of the folder.

3. A folder for sewing machines including upper and lower guiding members shaped so as to receive, direct and turn underneath the edge portions of a facing strip, the upper member being formed with a recess centrally thereof which increases in width toward the delivery end of the folder, a rib carried by the lower guiding member and located in said recess, a plate mounted on said rib, said plate having its receiving end vanishing into the lower guiding member and increasing in height toward the delivery end to a point well above the upper guiding member, and overlapping the edges of the upper guiding member alongside of 130

said central recess, said plate increasing in width from its front end to the delivery end of the folder, and a bridging member carried by the folder at the delivery end thereof and extending over the plate carried by said rib.

4. A folder adapted for use in sewing machines having four needles, said folder including upper and lower guiding members shaped so as to receive direct and turn underneath the edge portions of a facing strip, the upper member being formed with a recess centrally thereof which increases in

width toward the delivery end of the folder, and means associated therewith for forming 15 a plait from the body portion of the facing strip passing through the folder, said folder being so disposed relative to the four needles that lines of stitching adjacent the outer folded edges of the facing strip and adjacent the outer folded edges of the super- 20 posed plait will be formed.

In testimony whereof, I affix my signature.

JESSE J. HEAP.
